UNITED STATES PATENT OFFICE.

GEORGE W. PIGGOTT, OF NEW YORK, N. Y., ASSIGNOR TO HARTFORD CARPET COMPANY, OF HARTFORD, CONN.

DESIGN FOR CARPET.

Specification forming part of Design No. **11,375**, dated August 26, 1879; application filed August 2, 1879.
[Term of patent 3½ years.]

To all whom it may concern:

Be it known that I, GEORGE W. PIGGOTT, of the city, county, and State of New York, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

The groundwork of the carpet is divided into a series of rectangles, which are so placed as to interlock, and thereby take one or more corners off each rectangle. Thus the contiguous rectangles A and B interlock in manner stated; likewise the contiguous rectangles B and C; also the rectangles B and D; also the rectangles D and E; also the rectangles D and G. Between the figures C, E, and G is a figure, H, of irregular outline. Between the figures A and C is the rectangle F.

The several figures are provided with ornamental borders and decorated with floral designs. The figures B and H contain rich bouquets of flowers; likewise the figure A.

I claim—

1. The design for a carpet, consisting of the figures A, B, and D, substantially as shown.
2. The design for a carpet, consisting of the figures D, G, and H, substantially as shown.
3. The design for a carpet, consisting of the figures D E G, substantially as shown.
4. The design for a carpet, consisting of the figures C G H, substantially as shown.
5. The design for a carpet, consisting of the figures A B F, substantially as shown.
6. The design for a carpet, consisting of the figures A B C D E F G H, substantially as shown.
